UNITED STATES PATENT OFFICE.

NELSON H. TUNKS, OF TOLEDO, OHIO, ASSIGNOR TO FRANK B. HARRISON,
OF TOLEDO, OHIO.

BOLSTER GUIDE-BLOCK.

SPECIFICATION forming part of Letters Patent No. 703,503, dated July 1, 1902.

Application filed October 24, 1901. Serial No. 79,864. (No model.)

To all whom it may concern:

Be it known that I, NELSON H. TUNKS, a citizen of the United States, residing at Toledo, in the county of Lucas and State of Ohio, have 5 invented a new and useful Bolster Guide-Block, of which the following is a specification.

The object of my invention is the provision of improved means for controlling the end- 10 wise and vertical movements of a car-truck bolster relative to the truck-frame.

My invention consists in the combination, 15 with the bolster, of a guide or guide-block which is adapted to move relative to the same.

It further consists in certain novelties of construction and combinations of parts hereinafter set forth and claimed.

The accompanying drawings illustrate two 20 examples of the physical embodiment of my invention constructed according to the best modes I have so far devised for the practical application of the principle.

Figure 1 shows a car-truck in end elevation 25 with a part of the frame and a guide-bar broken away, so as to disclose the location of the guide-block upon the end of the bolster. Fig. 2 is a rear view of a guide adapted for use with a wooden bolster. Fig. 3 is a section of Fig. 4. Fig. 4 is a front view of the guide shown in Fig. 2. Figs. 5, 6, and 7 are 30 respectively rear, sectional, and front views of an example of the guide adapted for use with a Haskell & Barker or other truck-bolster, the vertical face or side of which is irregular in shape or other than a plain surface.

Referring to the several figures, the letter A designates a car-truck bolster; B, the 35 spring-plank; C, one of the bolster guide-bars, which are located each side of the end of a bolster; D, the top arch-bar of a diamond truck-frame; E, the bottom arch and tie bars; F, one of the guide-bar bolts; G, the 40 springs located upon the end of the spring-plank and beneath the end of the bolster; H, my improved guide or guide-block; I, the base-piece of the guide-block; J, a boss 45 upon the rear side of the base-piece; L, bolts 50 which secure the base-piece to the bolster, and

these bolts may extend entirely through the bolster end and also pass through the base-piece upon the opposite side of the bolster end, securing opposite guide-blocks in their proper positions; M, a recessed seat in the 55 face or front portion of the base-piece; N, a rotary flanged guide, which may be of any desirable shape, but which in the examples is shown of a circular form; O, the flanges of the guide-piece, and P a trunnion upon 60 the guide piece and located within the hole K of the base.

In the second example (shown by Figs. 5, 6, and 7) slight modifications are introduced, so that the base-piece will fit a bolster end, 65 which has an irregular-shaped face, such as I or E beams or a casting or the edges of a trussed metallic bolster, &c. The letter P designates a pin or cotter passed through the end of the trunnion to hold the flanged guide-piece. R designates the vertical and longitudinal strengthening-flanges of the base-piece, and S designates perforated lugs by 70 which the base-piece is secured to the bolster end.

The assembling of the parts is obvious to 75 any person familiar with the art.

In common practice the well-known type of bolster guide-block is rigidly secured to the end of the bolster or cast integral with it, 80 and the flanges thereof, which are in parallel vertical planes, engage the sides of the bolster guide-bar. When the car-body sways from side to side and when the bolster end moves upwardly and downwardly upon the 85 spring or springs, the bolster leaves its normal position, which is in a plane parallel with the top surface of the track-rails and occupies a position oblique to the said rails. It is clear that when thus disposed the flanges 90 of the guide-block will not be parallel with the edges of the guide-bar, and consequently the guide block and bar will bind and the bar or frame of the truck become distorted and racked. The same conditions will exist 95 when the springs at the opposite ends of the spring-plank are of unequal power, allowing the bolster to normally occupy an oblique position, and, moreover, when the frame is "out of square" or one side thereof has 100

sagged, and when the end of the bolster is nearer one wheel than the other, an analogous condition will prevail.

The application of my improvement will allow a free movement of a bolster end under all conditions of service, inasmuch as the flanged guides can rotate about the trunnion, and when the hole K is somewhat larger than the diameter of the trunnion the guide-piece can move in a horizontal plane. The use of my guide-piece will result in preventing the wear of the guide and guide-bar. The guide-bar, guide block, and bolts will not become broken, the arch-bars will not become distorted, the brasses will wear more evenly, and the frame will be kept approximately "square," inasmuch as the cramping or binding of the parts will be obviated.

While I have illustrated and described only two examples of the physical embodiment of my invention, I do not thereby intend to confine the scope thereof to such pictured examples, for the construction, shape, and form of the guide-block can be modified at will. The type of bolster used will determine the construction of the guide-block and the manner of its application. I may use the flanged guide independent of the base-piece, and such use is perhaps desirable in connection with a cast bolster where the hole for the trunnion may be made in the cast bolster.

All modifications and modes of application of the invention I intend to embrace within the scope of the claims.

What I claim as new, and desire to secure by Letters Patent, is—

1. The combination with a truck-bolster and a truck guide-bar, of a guide-piece, movable relative to the bolster.

2. The combination with a truck bolster and guide-bar, of a rotary guide-piece.

3. The combination with a truck bolster and guide-bar, of a guide-piece having an endwise motion.

4. The combination with a truck bolster

and guide-bar, of a guide-piece having a rotary and an endwise motion.

5. The combination with a truck bolster and guide-bar, of a movable guide-piece having a trunnion.

6. The combination with a truck bolster and guide-bar, of a guide-piece having flanges, and movable relative to the bolster.

7. The combination with a truck bolster and guide-bar, of a base-piece and a guide-piece, movable relative to the base-piece.

8. The combination with a truck bolster and guide-bar, of a base-piece having a hole, and a guide-piece provided with a trunnion.

9. The combination with a truck bolster and a guide-bar, of a base-piece having a seat, and a movable guide-piece located within the seat.

10. A bolster guide-block consisting of a base-piece, and a guide-piece, movable relative to the base-piece.

11. A bolster guide-block consisting of a base-piece having flanges and a movable guide-piece.

12. A bolster guide-block consisting of a base-piece having a seat, and a flanged and movable guide-piece.

13. A bolster guide-block consisting of a base-piece having a hole and a movable guide-piece provided with a trunnion.

14. A guide for a truck - bolster having flanges and a trunnion; the said guide being adapted to rotate when applied to said bolster.

15. A movable guide for a truck-bolster provided with flanges to embrace the edges of a guide-bar; and also having means for uniting the same to the end of a bolster in such a manner that the said guide can move relative to the bolster.

In testimony whereof I affix my signature in presence of two witnesses.

NELSON H. TUNKS.
